UNITED STATES PATENT OFFICE.

SAMUEL E. STEPHENSON, OF ATLANTA, GEORGIA.

SAMPLING APPARATUS.

Application filed March 26, 1927. Serial No. 178,802.

The invention relates to a sampling apparatus or machine and more especially to the class of automatic sampling machines for use in conjunction with elevator heads, conveyor openings, slides, or any place where materials are delivered.

The primary object of the invention is the provision of a machine of this character, wherein materials in predetermined amounts can be extracted from a chute or other delivery medium, for the sampling of such material, this being required in connection with apparatus for the milling or treating of flour, the machine being capable of use with equal facility in connection with the manufacture or treatment of other materials, wherein it is necessary or desirable that samples of material be periodically extracted for the purpose of inspection.

Another object of the invention is the provision of a machine of this character, wherein the construction thereof is novel in form and will automatically extract material in predetermined quantity and at determined intervals, without regard to weight or bulk.

A further object of the invention is the provision of a machine of this character, which is comparatively simple in construction, thoroughly reliable and efficient in its purpose, strong, durable, automatic in action and inexpensive to manufacture and install.

With these and other objects in view, the invention consists in the features of construction, combination and arrangement of parts, as will be hereinafter more fully described, in detail, illustrated in the accompanying drawing, showing the preferred embodiments of the invention and pointed out in the claims hereunto appended.

In the accompanying drawing:

Figure 1 is a top plan view of the sampling machine constructed in accordance with the invention, portions being broken away to show details.

Figure 2 is a sectional view on the line 2—2 of Figure 1 looking in the direction of the arrow.

Figure 3 is a side elevation of the machine, showing the chute for the material in vertical section.

Figure 4 is a fragmentary detailed view showing the sampling bucket in delivery position.

Figure 5 is a fragmentary sectional view on the line 5—5 of Figure 1.

Similar reference characters indicate corresponding parts throughout the several views in the drawing.

Referring to the drawing in detail, the sampling machine, comprises a bed or frame 10 having the major portion thereof of substantially rectangular form provided with an open center 11, while the remaining portion extends from one end of said rectangular shaped portion and is curved laterally to provide an arm or crane 12. The frame 10 including the arm or crane 12 is preferably made from metal cast or otherwise formed and has provided marginally thereof an upstanding reinforcing rib or bead 13, the bed or frame 10 being designed to be mounted in any suitable manner upon a foundation or support.

Formed on the side rails of the frame 10 are spaced pairs of journal bearings 14 and 15, respectively, and mounted in the bearings 14 is a shaft 16 which projects beyond the frame 10 at one side thereof and has keyed or otherwise made fast to this projecting end a belt pulley 17 constituting the power pulley for the machine. Mounted in the bearing 15 is a driven shaft 18, while arranged within the open center 11 of the frame 10 are gear wheels 19 and 20, and pinions 21 and 22, respectively. The gear wheels 19 and 20 are mounted loose upon the shafts 16 and 18, while the pinion 22 is made fast upon the said shaft 16 to mesh with the gear wheel 19 and the pinion 21 is made fast upon the shaft 18 to mesh with the loose gear wheel 20 as will be clearly obvious from Figure 1 of the drawing.

The pinion 21 is offset laterally relative to the gear wheel 20 and intermittently meshes with the latter through the medium of a toothed section 23 extended laterally from the perimeter of said gear wheel 20. This gear wheel 20 is at all times in mesh with a pinion 24 in alignment therewith and formed on the hub of the gear wheel 19 next to the pinion 21, the details of which will be apparent from Figure 1 of the drawing.

It will be apparent that motion is transmitted from pulley 17 through its shaft 16 to the pinion 22, gear 19, pinion 24, gear 20, pinion 21 from the sector 23, so that the shaft 18 will be intermittently rotated, while the shaft 16 is constantly rotated for a purpose presently described.

The shaft 18 extends beyond the frame 10 on that side remote from the side from which

projects the shaft 16 and on this projected end of the shaft 18 is fixed a disc 25 having formed therein a row of spaced holes 26, these from the innermost to the outermost in their location gradually increasing in distance from the axis or center of the disc 25 and in any one of the same is adapted to be detachably engaged a wrist pin 27 with which is pivotally connected a throw arm 28 or what is more properly termed a pitman, the latter having cross head connection at 29 with a reciprocating plunger or rod 30 slidably fitted in a guide bearing 31 formed at the free end of the crane or arm 12.

On the outer end of the plunger or rod 30 is a bail 32 in which is eccentrically pivoted a sampling bucket 33 having an open top and inner end, from the latter of which projects an extenuated lip 34 and this bucket 33 is adapted to be reciprocated through a suitable opening 35 therefor formed in the vertical wall of a material chute 36, so that material gravitating within the chute 36 can be caught in the bucket 33, that is to say a given quantity of such material corresponding to the capacity of the bucket 33.

Adjustably mounted upon the bearing 31 is a substantially L-shaped gage arm 37, which regulates the tripping action of the bucket 33 accordingly to the adjustment of said arm 37 relative to the bearing 31. The arm 37 has formed therein a series of spaced holes 38 in any pair of which are engaged bolts 39 which are screwed into the bearing 31 and in this manner the gage arm 37 is adjustably secured to the bearing for regulating the dumping or tripping action of the bucket 33 under intermittent movement thereof in the operation of the sampling machine.

It will be apparent that by adjustment of the gage arm 37 and also the pitman 28 the throw of the plunger or rod 30 can be increased or decreased and the periodical dumping of the bucket 33 can be altered at the fancy of the user of the machine.

In the operation of the machine the sampling bucket 33 is periodically moved inwardly and outwardly through the opening 35 in the chute 36 by means of the plunger or rod 30 and the driven mechanism of the machine. When the bucket 33 is moved inwardly of the chute it is automatically raised to receiving position for accumulating material delivered into the chute 36. On the outward movement of the bucket 33 from within the chute 36 it slides over the gage arm 37 and after reaching a predetermined point will automatically dump or drop to discharging position as shown in Figure 4 of the drawing, thereby delivering the sample of material to a point of deposit as will be clearly apparent. In the working of the machine the extraction of

sampling material will be periodically continuous and effected in an automatic manner.

Due to the fact that the mechanism is geared down so low it results in a very slow drive for shaft 18, disc 25, throw arm 28 and the elements attached to arm 28, consequently there would be no movement to any extent whatsoever of pinion 21, after sector 23 has passed the latter, and under such conditions sector 23 will properly mesh with pinion 21. The sector 23 is of the necessary length to provide, when meshing with pinion 21 a full forward and rear stroke for the arm 28 so the bucket will have the desired extent of shift thereby when moving in and out.

While there has been described in the foregoing what is considered to be the preferred embodiment of the invention, it is to be understood that various changes in the proportion and arrangement of parts may be resorted to within the scope and spirit of the appended claims. It is also thought that the construction and manner of operation of the device will be clearly understood and therefore a more extended explanation has been omitted.

What is claimed is:—

1. In a machine of the character described, a bed having a lateral offset guide arm, a reciprocating plunger working in the arm, a bucket eccentrically pivoted with the outer end of the plunger for dumping action, means on the arm for controlling the period of dumping of said bucket, and means supported by the bed for intermittently moving the plunger.

2. In a machine of the character described, a bed forming an open frame and having a curved laterally extending arm, spaced shafts arranged transversely of the open frame, a combined gear and pinion loosely mounted on one of said shafts, a pinion fixed to such shaft and opposing said loosely mounted pinion, a pinion fixed to the other of said shafts and meshing with said loosely mounted gear, a gear loosely mounted on said other shaft, meshing with said loosely mounted pinion and provided with a sector intermittently meshing simultaneously with said opposed pinions, a disc on that shaft carrying the loosely mounted pinion, a pitman adjustably connected eccentrically to the disc, a bearing formed on the free end of the arm, a plunger reciprocatingly movable in the bearing and pivotally connected to the pitman, a bail at the free end of the plunger, a dumping bucket eccentrically pivoted in the bail, and means carried by the arm and controlling the period of dumping of said bucket when actuated by the plunger.

3. In a machine of the character described, a bed forming an open frame and having a curved laterally extending arm,

spaced shafts arranged transversely of the open frame, a combined gear and pinion loosely mounted on one of said shafts, a pinion fixed to such shaft and opposing said 5 loosely mounted pinion, a pinion fixed to the other of said shafts and meshing with said loosely mounted pinion, a pinion fixed to the other of said shafts and meshing with said loosely mounted gear, a gear 35 loosely mounted on said other shaft, meshing with said loosely mounted pinion and provided with a sector intermittently meshing simultaneously with said opposed pinions, a disc on that shaft carrying the 40 loosely mounted pinion, a disc on the journal carrying the fixed pinion, a pitman adjustably connected eccentrically 10 to the disc, a bearing formed on the free end of the arm, a plunger reciprocatingly movable in the bearing and pivotally connected to the pitman, a bail at the free end of the plunger, a dumping bucket eccentrically 45 pivoted in the bail, means carried by the arm and controlling the period of dumping of said bucket when actuated by the plunger, and means for adjusting the last named 50 means to vary the dumping period of said bucket.

4. In a machine of the character described, a bed forming an open frame and having a curved laterally extending arm, spaced shafts arranged transversely of the 55 open frame, a combined gear and pinion

loosely mounted on one of said shafts, a pinion fixed to such shaft and opposing said loosely mounted pinion, a pinion fixed to the other of said shafts and meshing with said loosely mounted gear, a gear 35 loosely mounted on said other shaft, meshing with said loosely mounted pinion and provided with a sector intermittently meshing simultaneously with said opposed pinions, a disc on that shaft carrying the 40 loosely mounted pinion, a disc on the journal carrying the fixed pinion, a pitman adjustably connected eccentrically to the disc, a bearing formed on the free end of the arm, a plunger reciprocatingly movable in the 45 bearing and pivotally connected to the pitman, a bail at the free end of the plunger, a dumping bucket eccentrically pivoted in the bail, means carried by the arm and controlling the period of dumping of said bucket when actuated by the plunger, means for adjusting the last named means to vary the dumping period of said bucket, and a power pulley having connection with one of the journals for imparting motion to the 55 gears and pinions.

In testimony whereof, I affix my signature hereto.

SAMUEL E. STEPHENSON.
